(57) **CLAIM**

The ornamental design for a toy aircraft carrier, as shown and described.

DESCRIPTION

FIG. 1 is a front, top perspective view of a toy aircraft carrier, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof; and,
FIG. 9 is another perspective view of the toy aircraft carrier, shown in an alternative position.
The broken lines in the figures illustrate portions of the toy aircraft carrier that form no part of the claimed design.
